UNITED STATES PATENT OFFICE

GEORGE B. DOREY, OF EVANSTON, ILLINOIS, ASSIGNOR TO ENTERPRISE RAILWAY EQUIPMENT COMPANY, OF CHICAGO, ILLINOIS, A CORPORATION OF ILLINOIS

CAR DOOR

Application filed April 25, 1928. Serial No. 272,596.

My invention relates to improvements in car doors and more particularly to closures employing a plurality of sliding car doors adapted to meet in overlapping relation for the purpose of sealing an opening.

An object of my invention is to provide double doors wherein the meeting vertical margins of the respective doors will be of great strength and particularly adapted to provide efficient sealing contact.

Another object of my invention is to provide for necessary strength in metallic overlapping car doors, whereby the overlapping and main body portions of one door are disposed in the outer plane thereof, and said door provided with a depressed trough-shaped reinforcing construction which lies between the overlapping and main body portions whereby connection may be directly effected with an interior door post carried by said door.

A further object of my invention is to provide door construction whereby the main body portions of the doors may be utilized for the embossment of indicatory intelligible symbols or advertising symbols, and the strength of the doors thus enhanced.

A still further object of my invention is to combine a door, and door supporting attachments, in such a manner that the door, and its attachments will be coordinated to attain maximum strength and rigidity with a light weight door construction.

Other objects of the invention will more clearly appear from the description and claims hereinafter following.

In the drawings forming a part of this specification, Figure 1 is a side elevational view of a portion of a car showing my improvements in connection therewith. Figure 2 is a transverse vertical sectional view taken through one of the doors and on a line corresponding substantially to a line 2—2 of Figure 1. Figure 3 is a plan sectional view taken through the doors and on a line corresponding substantially to a line 3—3 of Figure 1. Figure 4 is a vertical, transverse, sectional, elevational view on an enlarged scale showing the upper and lower portion of the door in relation to the car

structure and taken on a line corresponding substantially to a line 4—4 of Figure 1. Figure 5 is an enlarged fractional elevational view of that portion of the door showing one of the door supporting brackets and rollers 55 together with a section of the door supporting track identified therewith. Figure 6 is an enlarged detail sectional view of the central portion of Figure 3 showing a modified construction. Figure 7 is a view similar to Figure 6 illustrating still another modification. Figure 8 is a view illustrative of still another modification from that shown in Figures 6 and 7.

In the drawings, my improvements are 65 shown as incorporated in connection with a so-called "automobile car" wherein very large door openings are usually employed, said openings being adapted to be usually closed by two doors, one of said doors corresponding 70 in size to the average door opening of box cars and being usually employed only for normal service and the other of said doors being in the nature of an auxiliary door and utilized only when the exigencies of the service require 75 large openings.

The said auxiliary door is usually provided with a heavy door post on the interior of the door which may move with the door and which provides a means for locking the door 80 relatively to the car structure from the inner side of the car, said door post usually having associated therewith a wooden block adapted to receive the cooperating members which are applied when the car is used in grain service. 85

In said drawings 10—10 denote the vertical side door posts of the usual door opening in the side of the car, each said post having an angle-shaped sealing member 110 on the outer side thereof, the car being provided with a channel side sill 11 reinforced adjacent the door opening by an angle member 12 and the floor boards are indicated at 13. Adjacent the top of the car there is a longitudinally extending side top member 14 which is reinforced throughout the path of movement of the door by a T-shaped section 15. As shown a combined door track and guide 16 extends throughout the path of movement of the door and below the same. Said track, which is 100

provided with an outer depending flange 17, is rigidly secured to a series of brackets 18 which are spaced lengthwise of the door.

- The two closure members are indicated at 5 A and B respectively, closure A being the auxiliary door and closure B being the main or normally employed door. Each closure member has marginal reinforcing elements or members of generally Z-shape at the upper 10 horizontal and rear vertical margins, as indicated at 19 and 20, respectively. Each of the upper horizontal marginal elements 19 has the inner and outer flanges thereof, as indicated at 21 and 22, respectively disposed in the inner and outer planes of the door, the connecting webs 23 between the said flanges defining substantially the depth of the door. The rear vertical marginal reinforcing elements 20 for each door are also formed 15 of Z-shaped section each having an outer flange 24 disposed in alignment with the flange 22 of the upper marginal member and the inner flange 25 is bent rearwardly in the form of a U shape 26 adapted to enclose the associated sealing angle member 110 when the door is in closed position. The web 27 of the said rear vertical marginal element is preferably of the same depth as the web 23 of the upper horizontal marginal element 19. 20
- 30 The front vertical margins of the respective doors A and B are reinforced by vertical elements or members 28 and 29 said elements being of different construction for the respective doors, inasmuch as the element 28 of door A is adapted to overlap the element 29 on door B. Said marginal element 28 is preferably in the form of a trough-shape having the base 30 lying at the inner plane of the door, and the walls or side sections thereof, as indicated at 31 and 32, extending outwardly therefrom toward the outer plane of the door, the section 32 extending substantially at right angles to the door and having a flange 33 disposed substantially in the outer 35 plane of the door, the outer end of said flange being preferably curved as indicated at 34 for the purpose of presenting a flared guideway within which the companion door B is adapted to extend. It will thus be noted that the said base 30, section 32 and flange 33 combine to present a Z-shaped element at the meeting edge of the door. The section 31 is preferably disposed in an inclined position relative to the base 30, thus presenting a depression 40 which is of wider extent adjacent the outer surface of the door than at the base thereof. The element 29 on the companion door B is preferably of channel shape with the web 35 thereof being adapted to engage with the section or web 32 of reinforcing element 28 on the door A, the flanges thereof 36 and 37, respectively, of the member 29 disposed on the inner and outer surfaces of the door, the flange 37 being extended beyond the inner 45 flange.

The main body of plate A is preferably formed of upper and lower metallic panels as indicated at 38 and 39 respectively, and likewise the body of door B is formed of upper and lower metallic panels, as indicated at 40 and 41 respectively. Each of the lower panels 39 and 41 is bent inwardly adjacent its lower margin, as indicated at 42 and thence downwardly, presenting a depending section as indicated at 43, thus providing a substantially Z-shaped lower margin. Inwardly of said depending flange 43, and secured thereto by rivets 44, is a facing plate 45. The space intermediate the facing plate and plane of the door is preferably filled by wood fillers 45. The door is reinforced on its inner surface by diagonal braces 46—46, said braces being preferably of U-shape section, and extended across the meeting edges of the upper and lower panels of the respective doors. 50

The panels 38 and 39 of door A at their forward edges are deflected inwardly as indicated at 47, and are attached to the inclined flange 31 of the trough-shaped beam or reinforcing element by rivets 48, the inclined relation of said flanges 47 and 31 permitting accessibility with reference to the rivets 48. 55

On the inner side of the door A there is a door post C of usual construction, said post preferably consisting of an angular-shaped member 50 having a flange 51 lying against the inner face of the door, and secured thereto by rivets 52, which extend through the base 30 of the trough-shaped reinforcing element. The member 50 is connected to the inclined wall 31 by braces 53, which are secured to the web 54 of the post 50 and the inclined section 31. Spaced from each other lengthwise of the beam or element 28, and disposed in the trough-shaped depression are a series of spacing fillers 55. Said fillers are formed with walls 56, 57 and 58 which are riveted to the respective side sections and base of the depressed portion of the door. 100

The lower panels of the doors are formed of relatively heavy plates and the upper panels of somewhat lighter plate, the body of the upper plate being rigidified by suitable indentations or embossments which are designed to rigidify the plate on various crosslines. 110

The embossments are preferably made to present identifying symbols or advertising symbols. In the present embodiment the door B is embossed with the monogram of a large railroad system as indicated by the rectangular border 59, having the portion intermediate said border rigidified by embossed lettering 60. The sections of door plate adjacent the monogram are preferably reinforced by meaningless embossments consisting of elongated corrugations 61 and triangular embossments 62. 120

The plate 38 of door A is shown by way of illustration as rigidified by an embossment descriptive of the railroad's operations, said 130

embossment including a continuous border 62 having curved corners 63, which at the lower corners are disposed substantially tangent to the diagonal braces 46, and the space intermediate said border is reinforced by embossed lettering 64.

At the respective upper and lower overlapping corners of the door A there are disposed corner caps 65 and 66 which are extended over the adjacent door B for the purpose of sealing the crevices at the junction of said doors. The upper sealing cap 65 consists of a gusset plate having the main portion 167 in the main plane of the door and an angularly related flange 68 extending above and overlying the web 23 of the upper horizontal marginal element 19, the flange 68, in combination with the overlying flange 33 of the said door forming an enclosing hood 20 for the companion door A.

The cap 66 at the lower corner of the door, Figure 1, includes a main section 69 extending in the direction of the main body of the door and an inwardly directed lower flange 70 extending beneath the door, the outer portion of said cap being flared as indicated at 71 to facilitate the overlapping relation of the doors. The upper corners of the doors A and B, other than that upon which the sealing hood 65 is employed, are each provided with a gusset plate 72, which effectively rigidifies the corner of the door and compensates for the light body plate employed.

Each door is carried on anti-friction bearings D of which there are two per door, disposed at the lower margin thereof. Each of said anti-friction bearings D includes a housing 73 having a roller 74 mounted upon a pivot 75. Said housing 73 includes a wall section 76 overlying the main or outer portion of the door and a wall section 77 overlying the inwardly offset depending portion, said respective portions being connected to their respective walls by rivets as indicated at 78 and 79 respectively. The outer and inner walls are extended downwardly below the outermost lower margin of the door and the pivot 75. The pivot is disposed partially in the plane of the depending wall portion 43 and retained in operative position thereby. The outer wall 76 is extended downwardly beyond the inner wall 77 and presents a U-shape guide 80 which embraces the depending flange 17 of the guide track 16 and prevents outward displacement of the associated door. The inner and outer walls 76 and 77 are united by an integral horizontally extending lateral wall section 81, and vertically extending lateral wall sections 82, and the inner and outer walls in combination with the U guide are further braced by vertically extending ribs 83. This arrangement of bearing thus provides an exceedingly strong and rigid connection be-

tween the various wall sections and operates to strongly rigidify the lower inner depending margin 43 of the door, and is conducive to light weight.

A different embodiment of the front edge construction of the doors is indicated in Figure 6. In this arrangement, the doors are indicated at E and F respectively. The door E includes an outer marginal reinforcing element 110 in the form of a Z-shape, which may be formed either by pressing from a plate or from a Z-bar rolled shape, as may be preferred. The main door plate as indicated at 111 is in the outer plane of the door and diverted inwardly by an inclined section 112 and thence in parallelism with and to overlie the inner flange of the outer member 110, as indicated at 113. On the inner face of the door there is disposed a door post 114 of Z-shape, riveted by one of its flanges to the Z-shaped element 110 and to the door plate by rivets 115. The post member 114 is further braced against the door plate by braces 116. In the channel provided by the offset door plate and Z-shaped element there are disposed filler brackets 117. The door F includes an outer vertical marginal element 118 of channel shape having unequal flanges 119 and 120 with the latter of greater extent and disposed in the outer plane of the door.

The body door plate 121, which is disposed in the outer plane of the door, is secured to the wide flange 120 of the marginal element 118 by rivets 122, and a bracing filler 123 is disposed on the inner side of the channel section 118 to brace the flanges 119 and 120 thereof. In this arrangement it will be appreciated that a single row of rivets may be utilized to secure the fillers 123, the marginal element 118 and the plate 121 together as compared with the two rows utilized in the construction heretofore described.

The embodiment of the invention illustrated in Figure 7 discloses a construction similar to Figure 6 with cooperating doors G and H but the construction of the door H corresponding generally to the door F is modified. The door H includes channel-shaped marginal element 200 having unequal flanges 201 and 202 with the latter of wider extent than the former and disposed in the inner plane of the door. The body of the door plate 203, which is disposed in the outer plane of the door, is directed inwardly at an incline as indicated at 204, and thence in parallelism with flange 205 of the channel member 200, and riveted thereto by rivets 206. A filler member 207 is disposed in the angle between the flanges of the channel member 200.

In the embodiment of the invention illustrated in Figure 8, the trough-shaped marginal reinforcing element 300 on the door J is provided, and has integral outstanding

flange portions 301 and 302 disposed in the outer plane of the door, the flange 301 forming the overlying flange for the companion door, and the flange 302 forming the portion which is connected to the associated body plate 303 which in this construction obviates the necessity of forming bends in the main door plate.

It will thus be noted that the arrangement 10 of doors and door bracing together with the supporting means employed, provides for great strength, with lightness of construction; also the overlapping arrangement of the doors affords great strength and light 15 weight. The overlapping arrangement of the doors also provides for a weatherproof joint between the meeting edges of the doors. The trough-shaped depression on the margin of the auxiliary door also provides for 20 strength and convenience in riveting the door post to the inner side of the door. The rigidifying of the door plates by the use of symbols, slogans and other embossed indicia provides for greatly enhanced value in the car 25 equipment, reduced cost of maintenance, due to the elimination of stencilling maintenance, and provides for strength in the door parts.

While I have herein shown and described 30 what I now consider the preferred manner of carrying out my invention the same is merely illustrative and I contemplate all changes and modifications that come within the scope of the claims appended hereto.

I claim:—

- 35 1. In a sliding car door formed of a metallic plate and having marginal elements of appreciable depth, said plate forming substantially the main body of the door and being disposed in the outer plane thereof, one 40 of said vertical marginal elements being trough-shaped in form and secured to said plate, and provided with portions extending at an angle to the main plane of the door, and additional portions, one of which is disposed 45 in the outer plane of the door to form a sealing member, and the other of which is disposed between the angular portion and in the inner plane of the door.
- 50 2. In a railway car closure including two closure members slidably mounted with respect to each other, each of said closure members being formed of appreciable depth and a predetermined one of said members having a marginal reinforcing element adapted to 55 overlap the associated closure member when said members are in closed position, said marginal element extending along the inner face of said predetermined member, said element having a flange lying on the outer face and 60 including walls disposed at an angle to the main plane of the closure member and a wall lying in the inner plane of said member, a relatively thin plate forming the main body of said predetermined member, said body 65 plate having the main portion thereof lying

in the outer plane of the predetermined member, and adjacent the overlapping element being deflected inwardly towards the inner plane of said predetermined member and secured to said marginal element; and a door post secured to the inner face of the predetermined member.

3. In a sliding closure member having a vertically extending marginal element of channel shape with the web thereof arranged substantially in the inner plane of the door, and the flanges extending outwardly therefrom, one of said flanges being inclined relatively to the web; and plate sheathing forming the main body of the door, said sheathing being deflected inwardly to overlie the inclined flange and being united therewith.

4. In a railway car, the combination with an opening; of oppositely sliding doors adapted to overlap when in closed position; vertical beams on the margins of the respective doors, the beam on the adjacent margin of the overlapped door consisting of a vertically disposed reinforcing member formed of U-shape section, one of the flanges of said U-shape section being secured to the main body of the plate, and the overlapping door including an angular marginal member having a flange disposed on the inner face of the door and a flange disposed on the outer face of the door, said outer flange being of flared section and adapted to overlap said U-shaped section on the companion door; and a door post secured to said marginal member and having a portion co-operating with the flared section for accommodating the U-shaped member therebetween.

5. In a closure sealing means having two relatively slidable closure members said members being arranged to meet in overlapping relation when the closure members are in closed position, said closure members being formed of appreciable depth and each having a body plate section disposed in the outer plane of each closure; and means providing a trough-shaped depression in one of said closure members intermediate the overlapping flange thereon and the main body of the plate, said depression being formed by a trough-shaped vertical marginal element having a base wall portion lying substantially in the inner plane of the closure member, and walls extending outwardly therefrom, one of said walls lying at an incline with respect to the inner and outer planes of the closure member and being united with the body portion of the body plate, said body plate adjacent the margin of the closure member being inwardly directed and united with the inclined wall of the trough-shaped element.

6. In a sliding car door having vertical and upper horizontal marginal reinforcing elements, said elements including flanges respectively extending in the outer plane and

- inner plane of the door; a body plate secured to the upper horizontal and to one of the vertical marginal elements of the door in the outer plane thereof, the other of said 5 vertical marginal elements co-operating with the body plate section of the door to form a trough-shape reinforcement adjacent the said vertical margin of the door, said trough reinforcement member including a flange disposed in the outer plane of the door and flaring outwardly; a door post carried by 10 said other marginal element; and a brace secured to said post and one side of said trough-shaped reinforcement.
- 15 7. In a railway car sliding door, a vertical marginal reinforcing element having a wall of appreciable depth corresponding to the depth of the door, said element having flanges extending in the inner and outer 20 planes of the door; a body section formed of plate and having the main portion thereof disposed in the outer plane of the door, said plate and said vertical marginal reinforcing element co-operating to form a trough- 25 shaped marginal reinforcing construction adjacent one of the vertical margins of said door; brackets conforming substantially to the shape of the trough and secured to the respective walls of said trough-shaped rein- 30 forcement for the purpose of maintaining the contour thereof; and a post carried by said door and secured to the means defining the trough-construction, and to said brackets.
8. In a railway car closure including two 35 oppositely movable closure members, one of said members being adapted to overlap the margin of the other of said members when said respective closure members are disposed in closed relation, the overlapping members 40 including vertical marginal reinforcing sections having inner and outer walls, one of which is disposed in the inner plane of the door and the other disposed in the outer plane thereof to form a sealing element; a 45 door plate comprising the main body section of the door, said door plate having the main portion thereof disposed on the outer face of the door and deflected inwardly adjacent the marginal edge thereof and secured to the 50 said reinforcing section substantially in the inner plane of the door; and brackets ex- tending between the said inwardly deflected portion of the plate and the reinforcing section, and arranged at intervals for the pur- 55 pose of bracing the latter, at points along its length relatively to the main body of the plate.

In witness that I claim the foregoing I have hereunto subscribed my name this 23rd 60 day of April 1928.

GEORGE B. DOREY.
